CHARLES A. S TEMPLE, OF GREENWOOD VILLAGE, ASSIGNOR TO HIMSELF AND STEPHEN E. TEMPLE, OF BOSTON, MASSACHUSETTS.

Letters Patent No. 89,092, dated April 20, 1869.

IMPROVED SAFETY-SWITCH.

The Schedule referred to in these Letters Patent and making part of the same.

To all persons to whom these presents may come:

Be it known that I, CHARLES A. S. TEMPLE, of Greenwood Village, of the town of Wakefield, of the State of Massachusetts, have invented a new and useful Safety-Switch for Railways; and do hereby declare the same to be fully described in the following specification, and represented in the accompanying drawings, of which—

Figure 1 denotes a top view of it, as applied to a main track and its turnout.

Figure 2 is a side elevation of the same.

Figures 3, 4, 5, and 6 are transverse sections, taken through the switch on the lines A B C D, respectively.

Figure 7 is an under side view of the switch.

In these drawings—

E E E' E are the rails of the main track, while F F' are those of the turnout, or sideling-track, they being arranged and supported on cross-sills G H I K, in manner as represented.

The switch is placed between the rails E E, and the rails E' E', of the main track, and is pivoted to and rests, near one of its ends, upon a cross-sill, L, arranged alongside of the sill H, the pivots of the switch being shown at a a.

The main parts of the switch are two rails, M M, each of which is curved, or bent, in manner so that they may diverge from one another, as shown in top view in fig. 1.

These rails M M, at their pivoted ends, are always in conjunction with the two main-track rails E E, so that a railway-car may pass from the said main-track rails, to and upon the said switch-rails, or from the said switch-rails to the said main-track rails. When, however, the switch-rail M, which is nearest to the turnout-rail F', is in conjunction with that rail, the other switch-rail M will extend a short distance by the outer side of the main-track rail E', which is furthest from the rail F'.

The two switch-rails M M rest on and are also pivoted, near their opposite ends, to a cross-bar, N, which is parallel to the sill L, and is formed in longitudinal section, as shown in fig. 6.

It rests on supports O O, so as to be capable of being moved, or slid endwise thereon, and is provided with shoulders, b b, to arrest its movements, by bringing up against the supports O O.

There rest on the bar N, two long auxiliary switch-plates P P', which are pivoted to the said bar, as shown, at c c, each being capable of turning horizontally on the bar, and toward and away from the next adjacent switch-rail M. On each of the plates P P', are two tapering tongues, which are formed and arranged in manner as shown at R S and R' S', their upper surfaces being level with those of the track and switch-rails.

The switch-plates rest also on a cross-bar, T, which extends underneath and is pivoted to the two rails M M.

There are intermediate supports to the switch-rails and plates, the same being as shown in figs. 3 and 5.

A bow-spring, U, arranged between the two plates P P', or a separate spring to each, serves to press each plate toward the next adjacent switch-rail M.

An arm, V, projects from each of the plates P P', underneath the next adjacent switch-rail M, and is constructed so as to engage with a lever-latch, W, applied to the outer side of the rail M, and pivoted thereto, the fulcrum, or pivot being shown at f.

A spring, y, fastened to the rail M, is employed to press down the lever-latch into engagement with the arm V, so as to hold the switch-plate closely against the switch-rail.

The tail of the lever-latch extends somewhat above the top of the switch-rail, and is formed with an inclined plane, g'.

When the switch is moved, so as to bring the tongues R R' into conjunction, or line with the main-track rails E E', the switch will be adjusted for a railway-carriage to pass from the rails E E, to the rails E' E', of the main track, or from the rails E' E', to and upon the rails E E, as the inner edges of the tongues will be in line with those of the main-track rails.

When, under ordinary circumstances, a common switch be in alignment with the main-track rails, and an attempt be made to run a car from the turnout, or sideling to and upon the switch, the car would be thrown off the track, because the switch would not be in alignment with the sideling; but, with my safety-switch, the car, in running from the sideling, or turnout-track to the main track, will have its wheels on one side run on the switch-rail M, in conjunction with the rail F' of the turnout, and the flanges of the wheels of that side will pass between the tongue R', and the next adjacent switch-rail M. Furthermore, each wheel, while running on the said rail M, will pass on the plane g' of the next latch-lever W, and will move the said lever so as to unlock the plate P' from the rail M. The wheel, continuing to move on, its flange will pass on between the switch-rail and plate, and the latter will give way so as to enable the wheel to continue its course on the switch-rail. The wheels on the other side of the car will run on the tongue S, and from thence upon the tongue R, and finally will enter upon the next adjacent switch-rail. In this way, the car will be made to pass from the sideling over the switch, and upon the main track, without accident, or being thrown off.

If now we suppose the switch to be set so as to direct a car from the main track to the turnout, in which case the tongues R R' will be in conjunction with the rails F F', one of the switch-rails M will be in conjunction with the main-track rail E', and the other rail E' will be in conjunction with the tongue S'.

Now if, under this last position of the switch, we suppose a car to be running on the track-rails E' E toward the rails E E, instead of being thrown off the

track, as it would be with an ordinary switch, -its wheels, on one side, will be upheld by the tongues S' R', and those on the other will run on the switch-rail M next them, and they will act on the next locking-lever W, so as to unlatch the plate P from the said rail M, in order to allow the flanges of the wheels to pass between the tongue R and the said rail M. After their passage may have been effected, the plate P, by its spring, will be borne up against the rail M, and will be locked thereto by the locking-lever, which will be pressed down by its spring. Thus it will be seen that the switch becomes a perfect safety-switch, to direct the cars along their course, even when its tongues R' may be out of alignment therewith.

The switch-plates, at or near their free ends, should have means of keeping them down upon their supports,

or preventing the said plates from being thrown up off the said supports, by accident, or by the action of the wheels of the car.

I claim the combination and arrangement of the two switch-rails M M, and their locking-lever latching-mechanisms, with the two switch-plates P P', provided with a spring or springs, and the tongues R S R' S', as described, the whole being constructed and arranged with and so as to operate with the main and turnout-tracks of a railway, substantially in manner as specified.

CHARLES A. S. TEMPLE.
